REVERSING TOY VEHICLE

Raymond Lohr and Richard Nelson Carver, Erie,
Pa., assignors to Louis Marx & Company, Inc.,
New York, N. Y., a corporation of New York

Application May 29, 1936, Serial No. 82,444

7 Claims. (Cl. 46—212)

This invention relates to toys, and more particularly to a self-reversing toy vehicle.

It has heretofore been suggested to provide a toy with bumpers or feelers at the front and rear ends thereof, which cause the toy to reverse on striking an obstruction. The primary object of the present invention is to generally improve reversing toy vehicles of this character.

A more particular object resides in the provision of reversing mechanism which is simple and inexpensive in construction and dependable in operation. Another object is to so arrange the reversing mechanism that it tends to automatically maintain itself in either extreme of its range of movement, that is, to maintain itself in mesh in the direction in which the vehicle is running. This establishes a slight but definitely noticeable and highly desirable resistance to shifting of the reverse mechanism from one extreme to the other, and in practice the shift takes place with a "snap action" as though the parts were being held in one extreme or the other by means of resiliently pressed cam mechanism or the like, yet no such mechanism is employed or necessary, and the desired result is instead obtained by advantageously selecting the position and direction of rotation of the gears in the driving gear train. The resistance to shifting is light enough so that the toy is readily reversed on striking an obstruction, yet is effective to prevent accidental or undesired reversing of the vehicle as it runs over irregularities or on an incline.

Further objects center about the governor and stop mechanism for the spring motor of the toy, and are to provide a governor of inexpensive type which may at the same time be employed as a positive stop or lock for the motor, and, most importantly, which will readily afford a slight rearward movement of a part of the gear train in order to accommodate meshing of the teeth of the gears during the reversing operation. Generally speaking, the governor is made in the form of an escapement rather than the more usual inertia device.

Still another object is to so arrange the reversing gear as to prevent free unwinding of the spring motor during the transition from one direction of operation to the other. Further objects center about the construction of the bumpers at the front and rear ends of the toy vehicle, and in accordance with our invention these bumpers are made of light readily yieldable and highly resilient metal. This is helpful in protecting the toy, and furniture or other objects which may be struck thereby, from injury, and is also function-

ally desirable in the operation of the toy, in that the resilient bumpers, while absorbing the impact, react to assist initiation of the reversing operation. The reversing operation, once carried half-way, is automatically completed by reason of the gear relationship referred to above. In accordance with a further feature and object of our invention, the bumpers may be additionally provided with rubber pads, preferably simulating vertical guards such as are commonly employed on automobile bumpers to prevent the bumper of one car from riding over that of another car.

To the accomplishment of the foregoing and other objects which will hereinafter appear, our invention consists in the reversing toy vehicle elements and their relation one to the other, as are hereinafter more particularly described in the specification and sought to be defined in the claims. The specification is accompanied by drawings in which:

Fig. 1 is a plan view of a reversible toy automobile embodying features of our invention;

Fig. 2 is a similar view, with the upper part of the body removed from the chassis or bottom wall;

Fig. 3 is a section taken in elevation in the plane of the line 3—3 of Fig. 2;

Fig. 4 is a transverse section taken in the plane of the line 4—4 of Fig. 2;

Fig. 5 is a section taken in the plane of the line 5—5 of Fig. 2; and

Fig. 6 is a side elevation of a modified form of toy embodying a further feature of our invention.

Referring to the drawings, the invention is shown embodied in a toy automobile the body 12 of which simulates a coupé, but it will be understood that other body forms may be used, and, in fact, the vehicle need not be an automobile. The vehicle body 12 is provided with front wheels 14 freely rotatable on a front axle 16, and rear wheels 18 secured to and driven by a rear axle 20. The toy is further provided with a driving motor, here exemplified by a spring motor having a main spring 22 coiled about a suitable winding stem 24 geared to the rear axle 20 by a suitable train of step-up gearing. This gearing includes reversing mechanism indicated generally at R in Figs. 4 and 5.

The vehicle is further provided with front and rear bumpers B which are connected to the reversing mechanism in order to reverse the direction of movement of the vehicle when it strikes an obstruction. The speed of the vehicle is limited by an escapement mechanism E rather than

by governor mechanism of the inertia type, and the escapement mechanism is also used as a stop to lock the spring motor against unwinding, this being under the control of a stop lever S.

5 Considering the arrangement in greater detail and referring more particularly to Fig. 5, the reversing mechanism comprises a gear 26 forming a part of the spring motor works, a direction-reversing idler or pinion 28 constantly meshing 10 with gear 26, and a pinion 30 mounted on the rear axle 20 of the vehicle. Axle 20 is itself received in slots 32 preferably extending horizontally in the side walls 34 of the motor works. The parts are so disposed that when axle 20 is 15 moved forwardly, it comes into mesh directly with gear 26, as is shown in Fig. 5. When, however, axle 20 is moved rearwardly, the axle pinion 30 is disengaged from gear 26 and instead comes into mesh with idler 28. In order that this reversing operation may take place without changing the elevation of the vehicle body, the slots 20 32 receiving axle 20 are arranged horizontally, and gear 26 is so centered that it comes somewhat below the elevation of pinion 30, so that 25 the pinion is brought into mesh with the gear by a small horizontal movement.

It should also be noted in Fig. 5 that all three gears entering into the reversing mechanism, that is, gear 26 and pinions 28 and 30, are 30 disposed closely together, so much so that pinion 30 reaches and enters into mesh with pinion 28 before it is completely disengaged from gear 26. In other words, pinion 30, in moving from gear 26 to pinion 28, is at no time entirely disengaged from both gear 26 and pinion 28. This prevents 35 free unwinding of the spring motor during the reversing operation.

The relative directions of rotation of the gears are also significant. Thus, referring to Fig. 5, gear 26 rotates in a counter-clockwise direction. 40 Consequently it tends to draw pinion 30 further into mesh, assuming, as is ordinarily the case, that there is at least some slight resistance to turning of wheel 18. This prevents accidental 45 dislodgement or shifting of the reversing mechanism. On the other hand, when the vehicle is running rearwardly, pinion 30 comes into mesh with pinion 28 which rotates clockwise. Pinion 28 therefore tends to move pinion 30 more securely into mesh with itself.

50 The only movable element in the reversing mechanism is rear axle 20. This is shifted forwardly or rearwardly by the bumpers B. More specifically, bumpers B are connected at the forward and rear ends of a bumper bar 36 which 55 extends along the chassis or bottom plate 38 of the vehicle, and which is reciprocably mounted thereon. The bumper bar 36 has secured thereto a transversely extending yoke 40, best shown in Fig. 4. The upwardly turned ends 42 of yoke 40 are recessed to receive the axle 20, as is clearly 60 shown in Figs. 3 and 5. It will be understood that as bumper bar 36 is shifted forwardly or rearwardly, it moves yoke 40 and with it the 65 axle 20, thus reversing the direction of operation of the vehicle.

Bumper bar 36 is held in place by a bearing 44 struck upwardly from bottom wall 38 near the forward end of the vehicle. It is further 70 supported by a bearing 46 (best shown in Fig. 3) struck downwardly from bottom wall 38 near the rear end of the vehicle. The bumper bar passes through the bottom wall, and the latter is cut away at 48 to receive the same. This construction 75 is adopted merely because the body of the

particular toy here under consideration is of the streamline type and is curved upwardly somewhat near its rear end, thus making it preferable to have the bumper bar come beneath the body at the rear end even though it projects above the bottom of the body at the forward end.

5 The bumpers are each made of a strip of thin sheet metal 50, the metal being bent into a loop the ends of which overlap at 52 and are there secured to the end of bumper bar 36 by suitable 10 tongue and slot connections 54. The metal used for the bumpers is highly resilient spring metal and is of very light gauge, the thickness being greatly exaggerated in the drawings. Because 15 of this construction, the bumper yields when the vehicle strikes an object, and then recoils, thus helping to absorb the blow or impact without damage and at the same time assisting the desired reversing operation.

The rear bumper is constructed like the front 20 bumper, but it will be noted that the bumper bar is turned upwardly at 56 in order to bring the bumper to a desired elevation approximately equal to that of the front bumper.

The bumpers may, if desired, be additionally 25 provided with rubber pads 58. These pads are open at their inner sides and are so slit that they may be sprung over the sheet metal strip 50 of the bumper, as is clearly evident from inspection 30 of Fig. 3 of the drawings. The pads 58 are preferably so shaped as to simulate the guards frequently employed on automobile bumpers in order 35 to prevent the bumper of one car from passing over that of another car. At the same time, the pads further eliminate danger of scratching or 40 damaging furniture during operation of the toy.

45 Considering the driving motor in greater detail, the motor is conventional in comprising a ribbon type spring 22 the outer end 60 of which is secured to the motor frame, and the inner end of which is secured to the winding stem 24. The end 62 of the winding stem is adapted to receive a suitable winding key. Winding stem 24 carries a main driving gear 64 which is connected to the 50 winding stem by appropriate ratchet mechanism including a dog 66 and a ratchet wheel 68, best shown in Fig. 3. Gear 64 meshes with a pinion 70 mounted on a shaft 72 carrying the gear 26 heretofore referred to.

55 In addition to the pinions of the reversing mechanism, gear 26 also meshes with a pinion 74 which forms a part of the governor mechanism of the toy. Pinion 74 is secured to and rotates a star-wheel or escapement wheel 76. An escapement member 78 is freely oscillatable on a shaft 80 disposed near wheel 76. It will be understood 60 that wheel 76 cannot turn freely within the escapement member 78, but that instead the latter must oscillate or vibrate about its support shaft 80 as wheel 76 rotates. This slows the speed of unwinding of the spring motor, thereby limiting the speed of the toy and so preventing damage to the toy or objects struck thereby.

65 There are several reasons why we prefer the present form of governor. One is that it may be conveniently employed as a positive stop member for locking the spring motor against rotation. Thus, referring to Figs. 2 and 3, it will be seen that while one end of shaft 80 is stationarily 70 received in motor frame wall 34, the other end, marked 82, is received in a slot 84 in the frame wall and is thus movable from the running or broken line position shown in Fig. 2 to the sloping 75 position shown in solid lines. In the latter

position, the escapement member 78 is brought into simultaneous engagement with the star-wheel at both the top and bottom, thereby locking the motor against unwinding. In the normal or retracted position, however, that is, the position shown in broken lines in Fig. 2, the escapement member 78 assumes an operating position which affords rapid but not excessive high-speed rotation of the star-wheel 76.

10 Referring now to Fig. 3, the slot 84 is provided with locating recesses 86 at its ends. The end 82 of the support spindle is normally urged downwardly by a hair-spring 88, thus holding the shaft and consequently the escapement mechanism in 15 either the locked or unlocked position. The shaft is moved by means of a pull strip 90 which projects through a slot 92 in the body of the vehicle, as is best shown in Figs. 1 and 3.

Another important advantage of the use of the present escapement mechanism as a speed-limiting governor, resides in the fact that the gear 26 of the reversing mechanism may, if necessary, move backwardly a slight amount, say a few degrees, during the reversing operation. This slight movement is necessary to accommodate the change of mesh of the gearing during the reversing operation, particularly when it is kept in mind that the wheels 18 are on the ground and therefore relatively immovable at the instant the vehicle is stopped. We have found that an ordinary high-speed inertia governor interferes with this readjustment of the gearing during the reversing operation, whereas the present escapement mechanism readily affords a range of movement of the gearing no matter how abruptly the vehicle is stopped from its normal rapid movement.

The vehicle may be run in either a straight line or on a curved path, and the steering mechanism for accomplishing this is of a comparatively simplified type. Specifically, one end of the front axle 16 is journaled in a flange 94 turned upwardly at one side of the vehicle. Ample material is available for this, because the bottom wall is cut away at this point to receive the front wheels, this being most clearly shown in Fig. 2 of the drawings. The opposite end of front axle 16 is journaled in a flange 96 at the opposite side of the vehicle, but flange 96 is provided with a slot 98 rather than a simple bearing hole. The ends 50 of slot 98 are recessed upwardly somewhat, as is indicated at 100. The axle is normally borne upwardly by a hair-spring 102, thus moving the front axle into either of the recesses 100. In the present case, one recess is so located that the axle 55 is disposed at right angles to the axis of the vehicle, this being the position shown in Figs. 2 and 3 of the drawings. The other recess is disposed rearwardly, and causes the axle and front 60 wheels to assume the position shown in broken lines in Fig. 2. To change from one position to the other, it is simply necessary to hold the movable front wheel and to shift the same to the desired position.

65 The middle portion of front axle 16 is shown bent or displaced upwardly somewhat, within the side flanges 94 and 96 and outside the side walls of the channel-shaped shift bar 36, but this is not essential and is provided in the present case 70 merely to establish ample clearance between the axle and the shift bar or bumper bar, which is located immediately therebeneath.

The body of the vehicle is made of two main pieces of sheet metal, one piece being upwardly dished to form the body 12, and the other piece

being relatively flat and constituting the bottom or chassis member 38. These two parts are secured together by appropriate tongue and slot connections, in accordance with conventional practices. If desired, the front end of the body or radiator simulation 104 may be made of a separate piece of sheet metal secured to the body portion 12 by suitable tongue and slot connections or like mode of attachment.

Referring now to Fig. 6, we show a modified form of reversing toy vehicle simulating a police emergency patrol auto. The mechanical features of this vehicle need not be described in detail, for the vehicle comprises rear wheels driven from a spring motor through a suitable reversing gear actuated by front and rear bumpers, just as has already been described. The present toy differs, however, in being provided with exposed figures, specifically a uniformed police driver 106 at the front or driver's seat, and a simulated captive 20 criminal 108 apparently held in the rear part of the patrol vehicle by another policeman 110. Figure 106 is freely pivoted at 112 and may be moved between the positions shown in solid and dotted lines. Similarly, the figures 108 and 110 25 are pivotally mounted on the vehicle at 114 and may be moved to either of the positions shown in solid and dotted lines. The pivoting of figures 108 and 110 at the point 114 is concealed by the bottom or floor 116 of the vehicle, the figures 30 passing through slots in the bottom 116. The parts are so balanced that when the vehicle is suddenly stopped by striking an obstruction, the figures all tumble forward, whereas when the vehicle is suddenly stopped from moving in a 35 rearward direction the figures all tumble rearwardly. The resulting action of the figures and the complete change in appearance of the toy are very amusing and increase the play value of the toy.

It is believed that the construction and operation, as well as the many advantages of our improved reversing toy vehicle, will be apparent from the foregoing detailed description thereof. The escapement acts as a speed governor which keeps the toy from running too fast and thus smashing too hard into furniture or walls, but is superior to the highly geared inertia type of governor, because it permits the gearing to turn backward a few degrees as the axle pinion shifts from one position to the other. The escapement is also readily employed as a stop or lock for the spring motor. The reverse gear is shifted by the bumpers, and the parts remain in either extreme position with an apparent snap action, because the direction of rotation of both the large gear and the direction-reversing idler is such that each tends to keep the axle pinion in mesh with itself and to drive the same still deeper into mesh. The reversing operation takes place as follows. The front bumper strikes an obstacle, and the bumper bar or shift rod begins to push the axle pinion out of mesh with the gear which somewhat resists the action and is therefore forced to reverse its direction very slightly in order to allow the axle pinion to unmesh. This slight reverse movement is freely permitted by the escapement type governor. Before the axle pinion unmashes entirely from the large gear, it begins to mesh with the idler pinion, and this prevents the motor from running free during the shifting operation. When the axle pinion is moved past center, it becomes entirely free of the large gear, and the spring of the motor again begins to unwind. The idler exerts a moving force

on the axle pinion, driving it fully into mesh and insuring completion of the reversing operation. Of course, in addition to the lineal motion, there is also exerted a circular or rotative motion which is transmitted from the axle pinion through the axle to the wheels. When the toy is stopped against movement, the floor acts as a focal point for this attempted rotative motion. Because of the above factors, it will be found that the 10 parent snap action of the gear shift does not manifest itself well when the toy is off the ground so that the rear wheels are free, nor when the motor is fully unwound so that there is no driving torque at all. In such case, the bumper bar may 15 be freely shifted back and forth and does not maintain itself in one extreme position or the other. The bumpers are highly yieldable and resilient, and may, if desired, be provided with rubber pads, thereby improving the operation of 20 the toy.

It will be apparent that while we have shown and described our invention in preferred forms, many changes and modifications may be made in the structures disclosed, without departing 25 from the spirit of the invention, defined in the following claims.

We claim:

1. A toy vehicle comprising a vehicle body, a front axle and front wheels therefor, a rear axle 30 and rear wheels therefor, the rear axle being journaled in slots to afford a slight forward or rearward movement of the rear axle, a pinion on said rear axle, spring motor-works including a driving spring and a train of step-up gearing 35 terminating in a large gear disposed near the aforesaid pinion, a direction-reversing idler pinion constantly meshing with said large gear and disposed adjacent the rear axle pinion, the arrangement of the parts being such that movement of the rear axle causes its pinion to engage either the large gear or the direction-reversing idler or both, there being insufficient space between the gears for simultaneous disengagement from both the large gear and the idler, highly 40 resilient yieldable bumpers at the front and rear 45 of the vehicle, said bumpers each being made of a strip or band of relatively light-gauge readily yieldable spring metal, and rigid means so interconnecting the bumpers and the reversing mechanism that the vehicle is reversed in direction 50 on striking an obstruction, the bumpers being made separately from and being secured to said rigid means.

2. A toy vehicle comprising an upwardly dished piece of sheet metal forming top and side walls 55 including wheel guards coming outside of the wheels, a bottom wall for closing the bottom of the vehicle body, said bottom wall being cut away at the front wheels, the metal of the bottom wall being turned upwardly inside the front wheels 60 and being apertured at one side to receive one end of the front axle and being slotted at the other side to receive the other end of the front axle, the slot being recessed to receive and hold the axle in any of several steering positions, and 65 resilient means bearing against the axle in order to hold the same in one of the recesses.

3. A toy vehicle comprising an upwardly dished piece of sheet metal forming top and side walls 70 including wheel guards coming outside of the wheels, a bottom wall for closing the bottom of the vehicle body, said bottom wall being cut away at the front wheels, the metal of the bottom wall being turned upwardly inside the front wheels

and being apertured at one side to receive one end of the front axle and being slotted at the other side to receive the other end of the front axle, the slot being recessed near its ends to receive and hold the axle in either a straight or angular steering position, and a spring secured to the bottom wall of the vehicle body and bearing against the axle in order to hold the same in one of the recesses. 5

4. A toy vehicle comprising a wheeled vehicle body, front and rear bumpers, a channel-shaped rigid bar extending longitudinally through and reciprocable in the vehicle body and carrying the aforesaid bumpers at its forward and rear ends, spring motor-works in said body including a driving spring and a train of step-up gearing, a pair of rear wheels mounted on a rear axle journaled in horizontal slots in the sides of the motor frame, a pinion on said axle, a direction-reversing idler adjacent said pinion meshing with a preceding gear in the gear train, the parts being so disposed that the rear axle on being moved slightly forwardly or rearwardly comes into engagement with the gear or with the idler and at an intermediate point is engaged with both and 20 cannot be disengaged from both during movement from one to the other, and means on the bumper bar for shifting the rear axle forwardly or rearwardly with the bumpers, the vehicle traveling in a forward direction when the axle has 30 been moved forwardly, and the vehicle traveling in a rearward direction when the axle is moved rearwardly. 25

5. A toy vehicle comprising a wheeled vehicle body, a driving motor therein, a train of gearing 35 between the driving motor and the wheels, said gear train including reversing gear mechanism, front and rear bumpers for automatically reversing the direction of the vehicle on striking an obstruction, and a governor for limiting the 40 speed of the vehicle, said governor including an escapement wheel and a freely oscillatable escapement member, the escapement mechanism being so arranged as to permit a slight readjustment of the position of the gears in the gear 45 train during the reversing operation. 50

6. A toy vehicle comprising a wheeled vehicle body, a driving motor therein, a train of gearing between the driving motor and the wheels, said gear train including reversing gear mechanism, front and rear bumpers for automatically reversing the direction of the vehicle on striking an obstruction, a governor for limiting the speed 55 of the vehicle, said governor including an escapement wheel and an oscillatable escapement member, the escapement mechanism being so arranged as to permit a slight readjustment of the position of the gears in the gear train during the reversing operation, and means to lock the escapement mechanism in order to hold the motor against unwinding. 60

7. A toy vehicle comprising a wheeled vehicle body, a driving motor therein, a gear train between said driving motor and the wheels, said gear train including reversing mechanism, means to automatically operate the reversing mechanism, a speed-limiting governor including an escapement wheel and an oscillatable escapement member adjacent the escapement wheel, and means to move the escapement member against 70 the escapement wheel in order to lock the motor against unwinding. 65
